Primary Examiner — Darlington Ly(74) *Attorney, Agent, or Firm* — Burr & Forman LLP(57) **CLAIM**

The ornamental design for a battery powered tool, as shown and described.

DESCRIPTION

FIG. 1 is a perspective view of a battery powered tool embodying our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The dashed broken lines of the battery powered tool in FIGS. 1-7 are illustrative of portions of the battery powered tool that form no part of the claimed design.

The dot-dash broken lines in the drawings illustrate boundaries between the portions of the battery powered tool that are claimed and not claimed.
